[57] CLAIM

The ornamental design for a video accessory device for a cellular telephone, as shown and described.

DESCRIPTION

FIG. 1 is a front, bottom, and right side perspective view showing of our new design for a video accessory device for a cellular telephone.

FIG. 2 is a left side elevation view thereof.

FIG. 3 is a front plan view thereof.

FIG. 4 is a bottom side elevation view thereof.

FIG. 5 is a top side elevation view thereof.

FIG. 6 is a right side elevation view thereof.

FIG. 7 is a back plan view thereof.

FIG. 8 is a left side elevation view showing an alternate embodiment of our new design for a video accessory device for a cellular telephone.

FIG. 9 is a bottom side elevation view thereof.

FIG. 10 is a top side elevation view thereof.

FIG. 11 is a right side elevation view thereof.

FIG. 12 is a back plan view thereof; and,

FIG. 13 is a back plan view showing an alternate embodiment of our new design for a video accessory device for a cellular telephone with a cover.

The portions of the second and third embodiment that are not shown in the drawings are the same as those shown in the first embodiment.
